UNITED STATES PATENT OFFICE.

LEROY S. BUFFINGTON, OF MINNEAPOLIS, MINNESOTA.

DESIGN FOR A LAMP-BODY.

SPECIFICATION forming part of Design No. 30,332, dated March 14, 1899.

Application filed February 13, 1899. Serial No. 705,441. Term of patent 7 years.

To all whom it may concern:

Be it known that I, LEROY S. BUFFINGTON, a citizen of the United States, residing at Minneapolis, in the county of Hennepin and State of Minnesota, have invented and produced a new and original Design for a Lamp-Body, of which the following is a specification, reference being had to the accompanying drawings, forming part thereof.

10 Figure 1 is a side elevation. Fig. 2 is a side elevation with some parts broken away. Fig. 3 is a front elevation, and Fig. 4 is a rear elevation of a lamp-body embodying my design.

15 The upper portion of the lamp-body has very much the appearance of a bell horizontally disposed, and the lower body-section of the lamp is approximately cylindrical in form, being slightly contracted where it joins the lower portion of the bell-shaped section.

20 When viewed from the front or looking into

the large and flaring end of the bell-shaped section, the face of the lamp at this point is shown to be concave, and a nipple-like projection having the appearance of a gas-burner is seen to project outward at the center of 25 this concave face.

The lamp-body in its general appearance is very suggestive of a "Quaker bonnet."

Having described my invention, what I claim as new, and desire to secure by Letters 30 Patent of the United States, is—

The design for a lamp-body, substantially as herein shown and described.

In testimony whereof I affix my signature in presence of two witnesses.

LEROY S. BUFFINGTON.

Witnesses:

M. M. McGRORY,
F. D. MERCHANT.
